HEAT-TREATING APPARATUS

Howard E. Somes, Detroit, Mich., assignor to
 Budd Induction Heating, Inc., Philadelphia,
 Pa., a corporation of Michigan

Application May 20, 1940, Serial No. 336,129

19 Claims. (Cl. 266—4)

This invention relates to induction heat treating apparatus and more particularly to a heating and quenching fixture especially adapted for the progressive heat treatment of internal walls of tubular objects.

In heat treating relatively long tubes it is preferable that the heating and quenching fixtures be supported from opposite ends so that congestion in the supporting arbor is minimized. In my Patent No. 2,261,333, granted April 28, 1942, the quenching fluid, cooling fluid as well as the conductors for leading the current into and out of the inducing coil are all arranged within the common support arbor and in such an arrangement it is difficult to provide a separate cooling water source and a separate quenching source, which is desirable in apparatus of this sort since safety in the use of such apparatus depends upon separate supply lines for cooling and quenching. Further, it is desirable that as great a volume of quenching fluid as possible be supplied to the apparatus to the end that the object being heat treated may be substantially instantaneously quenched, thus improving the efficiency of the apparatus.

It is, accordingly, an object of the present invention to provide an induction heat treat apparatus adapted for progressive operation in which the heating head and the quenching head are separable and introduced from opposite ends of a tubular object to be internally heat treated.

Another object of the invention is to provide an interacting heat treating head and quenching head of the type described in which proper positioning of the one with respect to the other is made essential before the flow of cooling fluid through the heat treating head may be effected.

A further object of the invention is to provide a heat treating head which is readily removable from its mechanically supporting arbor and in which electrical connections are quickly effected to concentric conductors of which the arbor is comprised.

Still another object of the invention is to provide a heat treating coil of several turns or more of the type described for progressive heat treatment in which the turn exposed to the greatest heat radiation from the workpiece is connected so as to be at a potential substantially that of the workpiece.

These and other novel features of the invention will appear more fully hereinafter from the following detailed description when taken in conjunction with the accompanying drawings illustrating a form of the invention and the

method by which the same may be produced. It is expressly understood, however, that the drawings are employed for purposes of illustration only and are not designed as a definition upon the limits of the invention, reference being had for this purpose to the appended claims.

In the drawings wherein similar reference characters refer to similar parts,

Figure 1 illustrates a modification of the invention illustrated in longitudinal section and Figure 2 is another modification of the invention likewise illustrated in longitudinal section.

Referring to Figure 1 there is illustrated a tubular workpiece 10 in which heat treatment is to be effected, for example the internal wall hardened to a substantially uniform depth as indicated at 12. Such heat treatment is effected through the generation of annular high frequency heating currents in the internal wall and adjacent layers of the workpiece by reason of the inducing coil 14 and the application of quenching fluid through the annular quenching nozzle 16, it being understood that the workpiece is moved downward with respect to the coil 14 and quenching nozzle 16 at a uniform rate.

The heat treating head, on which the coil 14 is mounted, is provided with a laminated iron core 18 in the window 20 of which are arranged the four turns of the inductor coil 14. The ends of the coil 14 are connected through terminal or lead fittings 22 and 24 to a concentric conductor arrangement, of which more will be said hereinafter, the lead 24 being brought through an insulating block 26, the latter interrupting the annular core for a sufficient sector as is necessary to provide proper insulation. The individual turns are insulated as at 28 from the core and from one another as illustrated at 30, and each turn preferably lies substantially in a plane perpendicular to the axis of the head, each turn being provided with an offset portion leading into the adjacent turn as indicated at 32, the offsets being substantially in line with the terminals 22 and 24.

The annular core 18 and insulating block 26 are supported upon a sleeve 34 between a recessed shoulder 36 on the sleeve and a recessed collar 38 and collar 40, threaded upon the sleeve. It will be observed that the turn connection 22 which is at the lower end of the inductor coil is made directly to an integral shoulder portion 42 of said sleeve, the same corresponding to the segmental portion of the core completed by the insulating block 26 and thus the lower end turn

of the inductor coil derives its energy through the sleeve 34 which is in turn connected to the exterior sleeve 44 of the supporting arbor generally indicated by the reference numeral 46. The other terminal 24 of the inductor coil 14 is provided with a tubular extension 28 extending through an integral sleeve-like portion 48 of the insulator block 26 through the sleeve 34 and through an internal insulating sleeve 50 and thence threaded into an inner central main support sleeve 52. The latter sleeve is readily insertable into the inner sleeve 34 of the arbor 46 and is secured thereinto by a central extending bolt 56 threaded into the collar 58 secured through threaded engagement within the center arbor sleeve 54. Thus electrical connection is made between the upper terminal of the coil and the center sleeve of the arbor, and it will appear that in effect the leads are cross-connected by the passage of the terminal 24 through the sleeve 48 to the inner support sleeve 52. In heat treatment the movement of the head upwardly relative to the work brings the upper turns of the coil adjacent relatively cold metal, whereas the lower turns are adjacent hot metal heated to recalescent temperature. It is, therefore, preferable that the turns adjacent the heated portion be substantially at the same potential as the work and this is accomplished by connecting the lower turns to the outer grounded sleeve 44 and grounding the work.

The main support sleeve 52 and sleeve 34 of the head are secured together through a shoudered collar 60 threaded upon the sleeve 34 and the shoudered collar is provided with a plurality of spring contact pads 62 which are adapted to make connection to the outer grounded sleeve 44 of the arbor 46.

In order to cool the inductor coil the same is tubular and its terminal connections are likewise tubular to provide a continuous passage for the flow of a coolant therethrough. As illustrated, cooling water preferably under pressure is supplied through the center sleeve 54 of the arbor, the same passing through bores 66 in the collar 58 and thence downward through an annular space 68 provided between the main support sleeve 52 and the center bolt 56, the bore of the tubular terminal extension 28 and thence through the hollow conductor to the other terminal 22.

The sleeve 34 adjacent the terminal shoulder portion 42 thereof is provided with a radial aperture 70 through which the coolant may pass. In order to prevent the flow of coolant through the coil at such times as the same is not operatively associated with the quenching head, a valve is provided within the end of the sleeve 34, which valve is opened through the positioning of the quench head in proper relation to the heating head. The valve is composed of a threaded annular hollow valve casing 72 threaded into the end of the sleeve 34, the hollow member being provided with a conical valve disc 74 carried on a stem 76, the latter being slidable within a socket 78 in the casing 72. A valve seat 80 for the conical valve 74 is formed in a collar 82 threadedly received in an aperture 84 in the underside of the casing 72. The hollow portion within the casing is adapted to be connected to the port 70 in the sleeve 34 through one or more apertures 86 through which such communication is established. The valve assembly is removable to provide access to the head 51 of the bolt 56 and suitable insulation 79 and 81 is provided between the

end of the bolt and the central support sleeve 52, the latter being secured in place by a threaded collar 83.

The quenching fixture or head 88 is provided with annular collars 90 and 92 threaded upon a shoulder 94 of the quench support tube 96 and communication to the annular quenching nozzle 16 is provided through the ports 98 in the support tube 96 and the ports 100 in the annular nozzle collar 90. The quench fixture 88 is provided with a pin 102 which is adapted to engage the valve 74 and open the same when the quench fixture or head 88 is in the position shown ready for quenching operation. Opening the valve permits the flow of coolant through the inducing coil through the valve seat sleeve 80 and into the recess 104 in the end of the quenching head 88 and from thence the cooling fluid is permitted to escape through the ports 100 into the space 108 through which the quenching fluid from the nozzle 16 flows. To assure concentricity of quench and heat treat head when together, the mating conical projection 101 and recess 103 on the head and quench respectively are provided.

Referring to the modification of Figure 2 considerable similarity will be seen between the structure there shown and that of Figure 1. The workpiece 10 is adapted to be heated by the inducing coil 14' arranged on a core 18, the latter being mounted upon a sleeve 110 between threaded and grooved collars 112 and 114, respectively, and the annular notch 116 in the support sleeve 110. The coil terminals 122 and 124 are connected to the sleeve 110 and the concentric central support member 126, respectively, in a manner similar to that disclosed in Figure 1. The support members or sleeves 110 and 126 have shoulders 128 and 130 between which a thin layer of insulation 132 having an offset 134 is clamped and the two sleeves or support members are secured together by an end collar 136 threaded on the inside of the end of the sleeve 110, the collar bearing against an insulating disc 140 thrust against the end of the inner support member 126. The coil terminals 122 and 124 are arranged in a suitable sector-shaped insulating block 142 likewise quite similar to that of Figure 1.

The assembly comprising the concentric support members 110 and 126 is secured in the main support arbor by a bolt 144 threaded into a transverse perforate partition 146 in the central arbor and support sleeve 148, the sleeve being carried by the end of a tubular member 150 located within an outer tubular member 152, the two members being insulated as at 154 by a sleeve extending the length of the arbor. Through this arrangement electrical connection is made between the central support member 126 and the arbor tubular member 150. Electrical connection is made between the outer support member 110 of the head to the outer tubular member of the arbor 152 through a shoudered end cap 156 threaded upon the exterior of the tube 152, the shouder 158 of which bears against the end of the tube 152 and an offset 160 in the insulation 154. The shouder 158 also carries a plurality of spaced resilient contact pads 162 which effect sliding electrical contact with the support member 110.

Through the above arrangement the head is reduced in weight and size by arranging the contact members 162 upon the arbor. In each of the constructions of either Figure 1 or 2 it will be noted that the concentric tubular arbor members

150 and 152 (Figure 2) or 54 and 44 of Figure 1 are not rigidly secured together at the lower end as shown but are relatively free to expand and contract relatively, the friction contact pads 162 or 62 being permitted to slide on their respective contact surfaces 111 of the outer support member 110 or the end portion 45 of the sleeve 44. Thus, it will appear that relative expansion and contraction, due to the fact that the internal conductor tube 150 may be better cooled than the external conductor tube 152 by reason of its forming a cooling water conduit leading to the inductor coil, may take place without stressing the parts. When it is considered that a supporting arbor may be of considerable length and that accurate centering of the heating coil within the work is of great importance, it will be appreciated that allowance for such expansion and contraction without the setting up of stresses which might throw the apparatus out of alignment is an important feature.

The flow of cooling fluid through the coil is controlled in the present modification through a ball check valve, the latter being composed of a valve seat member 164, a ball 166 and a ball retaining member 168, the seat and retaining members being threaded on the interior of the support member 110 at the end thereof and the retaining member being jammed against the threaded collar 138. The retaining member also is provided upon its outer surface with a block of insulation 170 to protect the same from electrical breakdown.

Through the central aperture 172 of the valve seat member, the pin 174 carried by the quenching head 176 projects so as to lift the ball from its seat when the quenching head is in proper position with relation to the heating head. The quenching head in the present modification varies from that of Figure 1 in that the members forming the annular nozzle 178 form an assembly by themselves. As illustrated the nozzle member 180 is threaded upon the nozzle member 182 and jammed against the shoulder 184 upon the latter. To vary the nozzle aperture, shims 186 may be placed between the shoulder 184 and the member 180 and the assembly may be retained in any desired assembled relation aside from whether the assembly is removed from the quenching head temporarily as may often be the case. The member 182 as shown is threaded upon the head as at 188 and provided with apertures 190 connecting with an annular groove 192 in the head 176, the latter being connected with the central bore 194 of the head through ports 196. A drainage port 198 is provided through the head so that cooling fluid passing through the check valve aperture 172 may escape into the quenching discharge annulus 200 and in order to prevent such discharge from unevenly affecting the freshly quenched surface of the work 10, the member 182 may have a suitable skirt 202 projecting downward to deflect the discharge fluid passing through the port 198.

There has thus been described a heat treating head together with its attachment to the supporting arbor and its cooperation with a separable quench. The readily detachable feature of the quench and heat treat head from their supports makes it possible to provide in an apparatus having the requisite work holder, quench operating head and heat treating head a plurality of heads and quenches of different diameters which are quickly interchangeable so as to heat treat various diameters of bores and varying materials.

The quenching head per se and the method of quenching are disclosed and claimed in my co- 75

pending application Serial No. 419,828, filed November 21, 1941, as a continuation-in-part of this application.

Though two modifications of the invention have been illustrated and described, it is to be understood that the invention is not limited thereto but may be embodied in various modifications and arrangements which may be made without departing from the spirit of the invention as will be apparent to those skilled in the art. For example, any of the features of either modification may in many instances be readily incorporated in the other, and such changes as become necessary in constructing heads and quenches of different sizes may be effected. Accordingly, reference will be had to the appended claims for a definition of the limits of the invention.

What is claimed is:

1. In an inductive heat treating head a multi-turn inducing coil, a support therefor comprising tubular concentric conductors, means for electrically connecting said coil at one end to the inner conductor, through a connection passing through and insulated from the outer tubular conductor, and means for electrically connecting the other end of the coil to the outer tubular conductor.
2. In an inductive heat treating head, a support comprising tubular concentric conductors, one end of the outer conductor extending beyond one end of the inner conductor, and the other end of the inner conductor extending beyond the other end of the outer conductor to provide an attachment shank, a multi-turn coil on said support arranged around the outer conductor at the first-named end, an electrical connection from said coil to the outer conductor substantially at one end thereof, and an electrical connection from the other end of the coil to the inner conductor passing through and insulated from said outer conductor.
3. In an induction heat treating apparatus having a multturn inducing coil for progressively heating the internal surface of an elongated hollow workpiece and of the character wherein the coil and workpiece are adapted to have relative longitudinal movement with the coil so closely adjacent the workpiece that during such relative movement the radiated heat of the portion of the workpiece under immediate heating by the coil tends to heat the trailing end of the coil to a temperature greater than the leading end thereof, a support for said coil comprising inner and outer conductors insulated from each other, the outer 45 of said conductors supporting said coil and being grounded and electrically connected to the trailing end of said coil and the inner of said conductors being electrically connected to the leading end of said coil.
4. In an inductive heat treating head, an inducing coil having a coolant passage therein, a support for said coil comprising concentric tubular conductors insulated from each other, said inner conductor having a coolant-conducting passageway, and electrical connectors between said conductors and the ends of said coil, the connector between said coil and inner conductor extending through and insulated from the wall of said outer conductor and having a passageway 55 in communication with the passages of said coil and inner conductor.
5. In an inductive heat treating head, inner and outer tubular conductors, the inner conductor being closed at one end and the outer extending axially beyond the inner to provide a coolant dis-

charge chamber within the outer and axially beyond said closed end, an induction coil surrounding said outer conductor and having terminal connectors, one connector being insulated from and extending through said outer conductor and being electrically connected to said inner conductor and the other connector being electrically connected to said outer conductor, said coil and connectors having a coolant conducting passage communicating through said one connector with the interior of said inner connector and through said other connector with said chamber.

6. In an inductive heat treating head, inner and outer tubular conductors, the inner conductor being closed at one end and the outer extending axially beyond the inner to provide a coolant discharge chamber within the outer and axially beyond said closed end, an induction coil surrounding said outer conductor and having terminal connectors, one connector being insulated from and extending through said outer conductor and being electrically connected to said inner conductor and the other connector being electrically connected to said outer conductor, said coil and connectors having a coolant conducting passage communicating through said one connector with the interior of said inner connector and through said other connector with said chamber, said chamber having an outlet opening and a valve means associated with said chamber for controlling the flow of coolant from said outlet opening.

7. In an inductive heat treating head, inner and outer tubular conductors, the inner conductor being closed at one end and the outer extending axially beyond the inner to provide a coolant discharge chamber within the outer and axially beyond said closed end, an induction coil surrounding said outer conductor and having terminal connectors, one connector being insulated from and extending through said outer conductor and electrically connected to said inner conductor and the other connector being electrically connected to said outer conductor, said coil and connectors having a coolant conducting passage communicating through said one connector with the interior of said inner conductor and through said other connector and a discharge port in the wall of the extending portion of said outer conductor with said chamber, said chamber having a first valve casing member intermediate said port and the closed end of said inner conductor to seal the space therebetween, a second valve casing member between said port and the extending end of said outer conductor, said second casing member having an outlet passage and valve means between said casing members for opening and closing said outlet passage.

8. In an apparatus for heat treating by electromagnetic induction, an inducing coil having a coolant passage therethrough, a support for said coil having an open end and a port through the wall of said end, said coolant passage communicating through said port with the interior of said open end, valve means within said open end for closing and opening the same to control the flow of coolant through said passage, port and open end, an arbor on which said support is carried, and securing means within said open end between said valve means and arbor for securing said support and arbor together, said valve means including a housing within said open end having a cooperable valve seat and valve, said housing and the valve seat and valve being removable as a

unitary structure from said open end to provide access to said securing means.

9. In an induction heat treating apparatus, a heating head having an inducing coil, said coil having a fluid cooling passage therethrough, a normally closed valve carried by said head for controlling the flow of cooling fluid through said passage, a quench head axially aligned and relatively movable into and out of a position of adjacent relationship with said heating head and having a discharge passage adapted to communicate with said valve when said heads are in adjacent relationship, and means responsive to the proper positioning of said heads in said position of adjacent relationship for opening said valve to permit cooling fluid to be discharged from said coil passage, through said valve and said quench head discharge passage.

10. In an induction heat treating apparatus, a heating head having an inducing coil, said coil having a cooling fluid passage therethrough and said head having an axially opening discharge passage for receiving cooling fluid from said coil passage, a quench head having an annular discharge nozzle and an axially opening cooling fluid passage therein having an exhaust port, said heads being relatively axially movable into and out of registering engagement with each other, said cooling fluid passage of said quench head in the registered positions of said heads being in communication with the discharge passage of said heating head to receive coil cooling fluid therefrom, and an annular baffle means of appreciable axial extent carried by said quench head and circumferentially surrounding said exhaust port to direct cooling fluid exhausting therefrom in a generally axial direction.

11. In an induction heat treating apparatus, a heating head having an inducing coil, said coil having a cooling fluid passage therethrough and said head having an axially opening discharge passage for receiving cooling fluid from said coil passage, a quench head having an annular discharge nozzle and a cooling fluid passage therein having an axially opening inlet, said heads being axially relatively movable into and out of end engagement with each other, said inlet in the engaged position of said heads being in open communication with said discharge passage to receive cooling fluid therefrom, and annular cooperative interfitting means on said heads circumferentially surrounding said inlet and the outlet of said discharge passage for axially aligning said heads and providing a seal against the discharge of coil cooling fluid from between said heads when in end engagement.

12. In an induction heating apparatus, a pair of inner and outer concentric conductors, an induction heating head having inner and outer tubular conductors and an induction heating element supported by said outer tubular conductor and having terminal connections with said tubular conductors, said inner tubular conductor having an end portion for abutting engagement with said inner concentric conductor, a tension member extending axially within said inner tubular conductor for securing said inner conductors together in axially abutting engagement, said outer tubular conductor having an electrical connection with said outer concentric conductor.

13. In an induction heating apparatus, a pair of inner and outer concentric conductors, an induction heating head having an inner tubular conductor, an outer tubular conductor and an induction heating coil carried by said outer tubu-

lar conductor, said coil having its terminals electrically connected with said tubular conductors, one of said inner conductors being arranged to telescopically receive the other, a bolt member extending axially within said inner tubular conductor and having a shouldered head end axially abutting an end portion of said inner tubular conductor and a threaded end threadably received by said inner concentric conductor for securing said inner conductors together, and means electrically connecting said outer concentric conductor with said outer tubular conductor.

14. In an induction heating apparatus, an arbor comprising inner and outer concentric conductors insulated from each other, an inducing head unitary assembly including inner and outer concentric conductors insulated from each other and an inducing coil supported by said outer head conductor and having electrical connections with said inner and outer head conductors, said inner conductors having overlapping electrical wiping engagement with each other and said outer conductors having overlapping electrical wiping engagement with each other, and detachable means for securing two of the overlapping conductors together.

15. In an inducing head for heating by electromagnetic induction, a pair of concentric conductors having overlapping shoulder portions, insulation between said conductors and said shoulders, an inducing coil carried by the outer of said conductors, electrical connections between said coil and said conductors, said conductors having end portions axially spaced from said shoulders, and means cooperating with said end portions for urging one conductor and its shoulder toward the shoulder of the other conductor to clamp the insulation therebetween.

16. In an induction heat treating head, a pair of concentric conductors having overlapping shoulders, insulation between said conductors and shoulders, said outer conductor at one end extending axially beyond the end of the inner conductor, means within the extending end of the outer conductor and engaging said end of the inner conductor to secure said conductors in assembled relation, and an inducing coil surrounding said outer conductors and having an electrical connection with the outer conductor and an electrical connection with the inner conductor, said last mentioned connection being insulated from and extending through the outer conductor.

17. In an induction heat treating head, a pair of concentric conductors having overlapping shoulders, insulation between said conductors and shoulders, said outer conductor at one end extending axially beyond the end of the inner conductor, insulated means threaded within the extending end of the outer conductor and exerting pressure against said inner conductor end

to secure said conductors in assembled relation, and an inducing coil surrounding said outer conductor and having an electrical connection with the outer conductor and an electrical connection with the inner conductor, said last mentioned connection being insulated from and extending through the outer conductor.

18. In an apparatus for heat-treating by electro-magnetic induction heating, first and second members, each having a terminal end, said members being relatively movable toward and away from each other to place said terminal ends into and out of end juxtaposition, an annular inducing coil surrounding and supported internally by the terminal end of said first member and having a coolant passage therethrough, the terminal end of said first member having a chamber therein for receiving coolant from the outlet end of said coil and having a discharge passage opening through the end thereof from said chamber, and a valve device carried by said terminal end of said first member and associated with said discharge passage, said valve device being automatically movable from an open-passage position to a close-passage position and normally closing said discharge passage when said terminal ends are out of juxtaposition, the terminal end of said second member having a part effective during relative movement of said terminal ends into juxtaposition to move said valve device into open passage position and to maintain said valve device in open passage position while said terminal ends remain in juxtaposition.

19. In a heat treating apparatus, a quench head having a quench discharge nozzle passage therein and a coolant passageway separate from said nozzle passage, a heating head having a coolant conducting passage for cooling the head during the heating function thereof, and a flow controlling valve normally closing said coolant conducting passage, said heads being relatively axially movable into and out of end juxtaposition with each other to respectively connect and disconnect said quench head passageway and said heating head coolant conducting passage, said heating head and quench head being operative when in juxtaposition to perform their respective heating and quenching functions, and means on said quench head to actuate said valve to open passage position during relative movement of said heads into juxtaposition to connect said coolant conducting passage and said quench head passageway and to maintain said valve in open passage position during connection of said last-named passage and passageway, whereby heating head coolant may discharge through said quench head passageway during the heating operation of said heating head and the discharge of quenching medium from said quench head.
